UNITED STATES PATENT OFFICE.

ERNST LABHARD, OF THALWILL, SWITZERLAND.

PENHOLDER.

1,425,984.

Specification of Letters Patent. Patented Aug. 15, 1922.

Application filed November 17, 1921. Serial No. 515,831.

To all whom it may concern:

Be it known that I, ERNST LABHARD, a citizen of the Republic of Switzerland, and resident of Thalwill, in the Canton of Zurich, Switzerland, have invented certain new and useful Improvements in Penholders, of which the following is a specification.

This invention has reference to pen-holders and its object is to so construct the same that the sleeve usually provided for the reception of the pen is adapted to pivot about a pin mounted transversely of and within the holder. The inner end of the said sleeve is hereby connected with and under the control of a spring-blade also mounted in the holder and tending to press the pen against the writing surface. The pen, when writing, may thus yield to any pressure and the writer is therefore not only enabled to write more smoothly but his fingers are also subjected to less fatigue than is the case with ordinary pen-holders.

In the accompanying drawings illustrating two desirable forms in which my invention may be embodied:

Fig. 1 shows a longitudinal section, partly in elevation, of the pen-holder according to the first construction;

Fig. 2 shows a section through line 2—2 in Fig. 1, and

Fig. 3 is a longitudinal section, partly in elevation, of a modified construction.

Similar parts are designated by like reference characters throughout the several views and the specification.

Referring to Figs. 1 and 2, representing the first form of construction, 1 designates a holder of tubular shape, 2 the sleeve adapted to receive the pen 3, and 4 a pin mounted in and transversely of the holder and serving as a pivot for the said sleeve. The inner end thereof has secured to it a spring-blade 5 of which the free end 6 rests on the inner face of the tubular holder, the spring-blade hereby having the tendency constantly to press the front end of the sleeve 2 and consequently the pen 3 against the writing surface. When writing, however, the pen may yield in the direction of the arrow, Fig. 1, with the advantages hereinbefore mentioned. A pen-holder so constructed is adapted especially for use of persons suffering from writing-cramp.

According to the modified construction,

Fig. 3, the one end 8 of the spring-blade 7 is fixed in the solid rear part of the otherwise tubular holder 1, while the other and free end 9 projects into and engages with the sleeve 2 pivoted at 4, the spring-blade 7 here also tending to press the pen 3 against the writing surface. Between its ends 8 and 9 the spring-blade 7 is made to rest on a pin 10 which is secured in a ring 11 and mounted transversely thereof and of the tubular holder 1. The said ring is hereby made slidabile on the holder and the latter provided with a longitudinally disposed slot 12 in such a way that the pin 10 extending through and guided by such slot, when the ring is adjusted in either direction indicated by the double arrow, is caused to press more or less strongly against the slightly downwardly curved spring-blade 7. This spring-blade, which is thus arranged and caused to act in the manner of a lever, may therefore be adjusted so that its end 9 exerts a greater or lesser pressure against the sleeve 2.

It will be easily understood that the devices described could also be applied in connection with the well known and different kinds of fountain-pens.

Having now fully described my said invention what I claim as new and desire to secure by Letters Patent is:—

1. In a pen-holder of substantially tubular form, the combination, with the sleeve adapted to receive the pen, of a pin mounted in and transversely of the front end of the holder and forming a pivot for the sleeve, and a spring-blade mounted in the holder, the front end of the said spring-blade engaging the inner part of the sleeve and tending to press the same and the pen against the writing surface, all as and for the purpose set forth.

2. In a pen-holder of substantially tubular form, the combination, with the sleeve adapted to receive the pen, of a pin mounted in and transversely of the front end of the holder and forming a pivot for the sleeve, a spring-blade mounted in the holder and engaging the sleeve and tending to press the same and the pen against the writing surface, and means to adjust the pressure of the spring-blade against the said sleeve.

3. In a pen-holder of substantially tubular form, the combination, with the sleeve adapted to receive the pen, of a pin mount-

ed in and transversely of the front end of the holder and forming a pivot for the sleeve, a spring-blade mounted in the holder and engaging the sleeve on the one hand and being fixed in the rear part of the holder on the other hand, a second pin mounted transversely of the central part of the holder and forming a rest for the spring-blade, and means to adjust the said second pin in rela-

tion to the spring-blade, all as and for the 10 purpose described and shown.

In testimony whereof I have hereunto set my hand in the presence of two subscribing witnesses.

ERNST LABHARD.
